UNITED STATES PATENT OFFICE.

ISAAC FINESILVER, OF NEW YORK, N. Y.

DESIGN FOR A KNOB.

SPECIFICATION forming part of Design No. 27,300, dated July 6, 1897.

Application filed May 7, 1897. Serial No. 635,597. Term of patent 7 years.

To all whom it may concern:

Be it known that I, ISAAC FINESILVER, of New York city, county and State of New York, have invented and produced a new and original Design for Knobs, of which the following is a specification, reference being had to the accompanying drawing, which represents a perspective view of my newly-designed knob.

The leading feature of my design consists of a knob having an annular body, a doubly beaded and grooved head, a doubly-flaring stem, and a circular foot.

a represents the head of the annular knob, having an upper bead *a'*, a lower bead *a²*, two

intermediate cylindrical sections *a³* *a⁴*, and a central groove *a⁵*. Beneath the head *a* there is the contracted cylindrical stem *a⁶*, having an upper and a lower flaring end and joining the circular foot *a⁷*. The upper face of head *a* is provided with a bead *a⁸*, concentric to bead *a'*, and a central circular section *a⁹*.

What I claim is—

The design for a knob, substantially as herein shown and described.

ISAAC FINESILVER.
